LUBRICATOR PUMP AND RESERVOIR
ASSEMBLYRalph F. Urso, Detroit, Mich., assignor to McCord
Corporation, Detroit, Mich., a corporation of
Maine

Application April 10, 1946, Serial No. 660,984

11 Claims. (Cl. 184—27)

1.

This invention relates to lubricator construction and has particular reference to certain new and useful improvements in connection with the construction and arrangement of the parts thereof.

Principal objects of the invention are to provide:

A new and improved lubricator construction;

A lubricator construction which is rugged in design;

A lubricator construction in which the parts thereof are constructed and arranged so that different types of lubricator assemblies may be made from the same parts;

A lubricator construction embodying self-contained pump and drive units;

A lubricator construction in which the parts of the reservoir are designed so as to make it possible to build reservoirs of different sizes on an economical and efficient basis;

A lubricator assembly comprising a pump unit, a drive unit, and a case unit in which said units are all readily detachable each from the other;

A lubricator construction in which a drain partition and connector unit is employed to connect parts of the reservoir;

A lubricator construction embodying provisions whereby the driving connection of a lubricator may be changed from one end thereof to the other in the field without any machining operations;

A lubricator construction in which a unit is provided for supporting the pump and drive units independently of the side walls of the reservoir;

A lubricator construction embodying a hanger mounting for the pump and drive units therefor.

Other and further objects of the invention will be apparent from the following description and claims and will be understood by reference to the accompanying drawings, of which there are three sheets, which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

In the drawings:

Fig. 1 is a side elevational view with parts

broken away of a lubricator embodying the invention;

Fig. 2 is an enlarged fragmentary longitudinal sectional view thereof;

Fig. 3 is a cross-sectional view, taken generally along the line 3—3 of Fig. 2;

Fig. 4 is a fragmentary view similar to Fig. 3 but illustrating a modified form of hanger unit;

Fig. 5 is a sectional view taken along the line 5—5 of Fig. 2, with a part thereof broken away;

Fig. 6 is a fragmentary plan view taken along the line 6—6 of Fig. 2; and

Fig. 7 is a cross-sectional view taken generally along the line 7—7 of Fig. 2.

15 A lubricator embodying the invention comprises in general a reservoir unit 10, one or more pump units 12, and a drive unit 14 for each of the pump units. The reservoir unit, as illustrated, includes two sections 16 and 18 connected by a drain partition and connector unit 20.

20 Each of the sections of the reservoir unit includes side walls 22 and a bottom wall 24 which preferably are made by bending a piece of sheet metal stock in the form of a channel, as shown in Fig. 7, so as to form the bottom and side walls of the reservoir. Each end of each of the channel sections is closed by an apertured end wall 26, which is provided by a relatively heavy piece of sheet stock or plate, which at its sides and bottom is welded or otherwise suitably secured to the end of the piece which forms the bottom and side walls of the reservoir.

25 Thus, by employing various lengths of sheet stock to form the channel which defines the sides and bottom of the reservoir sections, reservoir sections of various lengths may be readily obtained. In the present instance I have shown two sections 16 and 18 of different lengths connected together by the drain partition and connector unit 20. This comprises a double walled, hollow partition which is sandwiched between and secured to the end wall plates 26 of two aligned sections and secured thereto by bolts 30 having nuts 32 on the threaded ends thereof.

30 35 40 45 The bolts 30 extend through holes in the end wall plates 26 and in the partition unit 20, and in one section the heads of the bolts 30 seat against the end wall plate 26 thereof, while in the other reservoir section the nuts 32 seat against the end lock washers which in turn seat against the end wall 26 of such section. In this manner the sections 16 and 18 are rigidly secured together as a unit.

50 55 Supporting and securing brackets 34 are secured to the under side of the bottom walls 24 of the reservoir sections 16 and 18 at each end thereof. A suitable gasket or sealing material is

provided between the partition 20 and the end wall plates 26 so as to effectively seal the same. The space within the drain partition is provided with drain holes 38 on each side thereof, as illustrated in Fig. 5, in order to permit the escape from the hollow drain partition of any fluid that may escape thereinto from either of the tank or reservoir sections. This will serve to prevent contamination of the fluid in one tank by the fluid in the other tank in the event of leakage from the tanks around the drive shaft which extends through the hollow drain partition.

The drive or hanger units 14 are mounted on rods 42. One end of each of the rods is reduced and arranged in a socket provided in a mounting bracket 44 detachably secured to an end plate 26 by bolts 46, as shown in Figs. 6 and 7. Set screws 48 are employed to retain the ends of the rods 42 in the sockets in the mounting bracket 44. The other ends of each of the rods 42 may be mounted on the end wall 26 at the other end of the reservoir section in the same manner as that just described, or they may, as illustrated, be secured to the end wall 26 at the other end of the reservoir section by means of a screw 50 which is threadedly secured in a threaded socket in the end of the rod 42, and the head of which screw 50 is seated in a hole in the end wall 26.

The drive unit 14 comprises a frame 82 having holes or guides 52 which receive the rods 42 whereby the drive unit is dependingly supported by the rods within the reservoir. Each drive unit includes a rotary cam or eccentric 54 which is provided with a hexagonal hole for receiving the drive shaft 56. A connecting rod 58 is provided with a bearing or sleeve 60 which is journaled on the eccentric 54. The other end of the rod 58 is connected by a pin 62 to one end of a rocker arm 64. The rocker arm or lever 64 is pivoted on a pin 66 carried on bracket arms formed on the frame member of the drive unit, and the other end 68 of the rocker arm 64 is bifurcated and arranged in straddling relationship relative to the actuating rod 70 of the pump piston 72 and between adjustable abutments 74 and 76 on the rod 70 whereby rotation of the shaft 56 will cause reciprocation of the piston 72.

The piston 72 forms a part of the pump unit 12 which further includes the pump body 78. The pump body 78 rests upon the upper surface 80 of the frame or hanger 82 of the drive unit 14, such frame 82 being provided with a plurality of tapped and threaded holes 84 which receive the threaded ends of bolts 86. The bolts 86 extend through holes in the pump body 78 and the heads of such bolts are countersunk therein and bear against the pump body 78 for securely clamping the pump unit is mounted on the hanger and secured in operative relation with the driving mechanism thereof.

The pump body is formed to provide a cylinder 88 in which the piston reciprocates. One end of the cylinder is provided with a port 90 which forms an inlet and discharge port therefor. Lubricant from the reservoir is supplied to the pump cylinder through filter 92, intake pipe 94, duct 96, past check valve 98, through sight feed indicated generally at 100, through duct 102, chamber 104, past check valves 106 and 108, and duct 110 which communicates with the port 90. The suction produced on the retractile stroke of the piston 72 communicated through the passage 102 to the interior of the sight feed 100 causes lubricant to flow upwardly through pipe 94, duct 96, 75

and pipe 97, from the down-turned upper end 99 of which the lubricant drops into the interior of the sight feed 100. From the interior of the sight feed, the lubricant is conducted to the cylinder 88 by the passage 102 and past check valves 106 and 108. A plug 112 partially fills the duct 110 above the check valve 108 and serves to keep the same in operative relationship relative to its seat.

Lubricant discharged from the cylinder 88 on the discharge stroke of the piston escapes through port 90 and past check valves 114 and 116 into a coupling 118 to which a feed line (not shown) is connected for conducting lubricant to the bearing to be lubricated.

Lubricant from the reservoir is sucked into the pump on the intake stroke of the piston and discharged from the pump on the discharge stroke thereof, the piston 72 being reciprocated by the drive shaft 56 as previously described. By adjusting the abutments 74 and 76 on the shaft 70, the stroke of the piston 72 may be varied.

While only a limited number of pump units 12 and drive units 14 therefor have been illustrated, I contemplate that a number of such units may be arranged in side-by-side relationship along the length of the reservoir. In addition, in lieu of employing a pump of the construction as illustrated, other types of standard pumps adapted for other lubricants and applications may be employed. In other words, the type of pump unit 12 illustrated is exemplary of a pump unit which may be detachably, operatively associated with the drive unit 14. If desirable or required, one type of lubricant may be employed in the reservoir section 16 and a different type of lubricant may be employed in the reservoir section 18.

In cases where one of the reservoir sections 16 may be relatively long, a hanger or frame 182, as shown in Fig. 4, may be employed. This frame is generally similar to that illustrated in Fig. 3, but includes a portion which is adapted to seat on the bottom wall 24 of the reservoir section so as to provide support for the rods 42 intermediate the mounting thereof. In other words, a hanger like that shown at 182 may be employed as one of the drive units at the center of the reservoir section 16, while the other drive units may be as illustrated in Fig. 3.

The partition and drain unit 20 is provided with bearings 130 in which a short shaft 132 is journaled, the shaft having drive heads 134 secured to the ends thereof which project beyond the bearings 130. Seals 136 are provided around the shaft 132 and thrust washers 138 are arranged between the drive heads 134 and the end walls of the partition unit 20.

A coupling sleeve 140 is provided between one end of the shaft 56 and the drive head 134, and a spacer or thrust sleeve 142 is suitably secured on the shaft adjacent the coupling sleeve 140. In this manner the drive shaft 56 in one of the reservoir sections is drivingly connected to the drive shaft in the other reservoir section so that both shafts and the drive units of the pump mechanism associated therewith will be driven together.

The other end of the shaft 56, as shown in Fig. 2, is supported on a pilot shaft 144 which is journaled in a bearing 146 provided in a closure plate 148 for the aperture in the end wall 26, such closure plate being detachably secured to the end wall 26 by means of bolts 150. The pilot shaft 144 projects through a seal 152 so that an oscillating arm 153 or other driving means may be

secured to the shaft 144. The shaft has secured thereto within the reservoir a pawl carrier 154 having pawls 156 thereon. The pawls 156 are operatively related to the ratchet wheel 158 which is fixed on the end of the shaft 56 in driving relationship therewith. Thus oscillation of the shaft 144 will function to drive the shaft 56 in one direction for operating the pump units, as previously described.

The shaft 160 projecting from the far end of the reservoir unit 18 may be similar in construction to that illustrated in Fig. 2, or such shaft may be directly connected to the drive shaft 56 within the reservoir section 18 whereby the drive shaft 56 will be driven directly with the shaft 160. Obviously, any type of power and drive arrangement may be applied to the shafts 144 and 160 for driving the same in accordance with the results desired from the lubricator.

It should be noted that the pawl carrier 154 as shown in Fig. 2 is in a different position from that as shown in Fig. 7. When the closure plate 143 is removed, the shaft 144 will be removed therewith. The shaft 56 may then be withdrawn from the drive units, or it may be removed with the drive units and the rods 42 as a unit.

The top of the reservoir between the pump units 12 may be closed by plate or cover sections 162, certain of which may be provided with necks 164 by means of which the reservoir sections 16 and 18 may be filled with lubricant.

While I have illustrated and described a preferred embodiment of my invention, it is understood that this is capable of modification, and I therefore do not wish to be limited to the precise details set forth but desire to avail myself of such changes and alterations as fall within the purview of the following claims.

I claim:

1. Lubricator construction comprising a pair of spaced and aligned lubricant reservoirs, each having an apertured end wall and a drive shaft, a pump driven by each of said shafts, a hollow partition sandwiched between and secured to both of said apertured end walls so as to form a unit with said reservoirs and closing the aperture in each of said end walls so as to separate the contents of said reservoirs, said hollow partition including spaced wall portions provided with bearings, a shaft journaled in said bearings and connected to said drive shafts, and a drain outlet from the space enclosed by said walls.

2. Lubricator construction comprising a pair of spaced and aligned lubricant reservoirs, each having an end wall, a pump associated with each of said reservoirs for pumping lubricant therefrom, a hollow partition sandwiched between and secured to both of said end walls so as to form a unit with said reservoirs and so as to separate the contents of said reservoirs, said hollow partition including spaced wall portions provided with bearings, and drive shaft means journaled in said bearings and connected to said pumps for operating the same and a drain outlet from the space enclosed by said walls.

3. Lubricator construction comprising a pair of aligned lubricant reservoirs, a pump associated with each of said reservoirs for pumping lubricant therefrom, a hollow partition sandwiched between and secured to both of said reservoirs so as to form a unit therewith and separating the contents of said reservoirs, said hollow partition including spaced wall portions provided with bearings, drive shaft means journaled in said bearings and connected to said pumps for operating the same, and means including shaft sealing means associated with said drive shaft and said partition to prevent the flow of lubricant along said drive shaft from one of said reservoirs to the other.

the same, and a drain outlet from the space enclosed by said walls.

4. In a lubricator a reservoir having rods extending across the same, a hanger suspended on said rods, driving mechanism including a shaft mounted on said hanger and a pump unit detachably mounted on said hanger and including an operating element positioned to be actuated by said driving mechanism and an intake arranged to be supplied with lubricant from said reservoir.

5. In a lubricator a reservoir having rods extending across the same, a plurality of drive units, each comprising a hanger suspended on said rods, and driving mechanism mounted on said hanger, a pump unit detachably mounted on each of said hangers and including an operating element positioned to be actuated by said driving mechanism thereof and an intake arranged to be supplied with lubricant from said reservoir, and a drive shaft mounted on said hangers.

6. In a lubricator an elongated reservoir having rods extending lengthwise across the same and detachably mounted on the end walls of said reservoir, a hanger mounted on said rods, driving mechanism including a shaft mounted on said hanger and a pump mounted on said hanger and including an operating element positioned to be actuated by said driving mechanism and an intake arranged to be supplied with lubricant from said reservoir.

7. Lubricator reservoir construction comprising a channel-shaped sheet metal member defining the bottom and side walls of a reservoir, end plates formed of materially heavier stock than that of which said channel-shaped sheet metal member is formed, one of said end plates being secured within and at each end of said channel-shaped member and forming the end walls thereof, and a pump and drive means therefor entirely supported on said end plates independently of said side walls, said pump having an intake arranged to be supplied with lubricant from said reservoir.

8. Lubricator construction comprising an elongated reservoir having bottom, end and side walls, said end walls being made more substantial than the side and bottom walls, frame means interconnecting said end walls and unattached to said side walls, a pump and drive means therefor supported on said end walls by said frame means independently of said side walls, a cover for said reservoir unattached to said pump and drive means and removable separately therefrom, said pump having an intake arranged to be supplied with lubricant from said reservoir.

9. Lubricator construction as defined in claim 8 wherein the side walls of said reservoir are formed of sheet metal.

10. A lubricator pump and reservoir assembly comprising a pair of aligned lubricant reservoirs, each having an end wall, a pump associated with each of said reservoirs for pumping lubricant therefrom, said end walls forming at least part of a partition which is arranged between said reservoirs and secured to both of said reservoirs so as to form a unit with said reservoirs and so as to separate the contents of said reservoirs, said partition being provided with bearings, drive shaft means journaled in said bearings and connected to said pumps for operating the same, and means including shaft sealing means associated with said drive shaft and said partition to prevent the flow of lubricant along said drive shaft from one of said reservoirs to the other.

11. Lubricator construction comprising a case unit forming a reservoir, frame means secured to said case unit, a drive mounted on said frame means, a pump unit mounted on said drive unit and having an operating element positioned to be actuated by said drive unit, and an intake arranged to be supplied with lubricant from said reservoir, said pump and drive units being constructed and arranged so as to be readily detachable as a unit each from the other and from said frame means and case unit, said pump unit being disposed on the top of said drive unit and said case unit and arranged exteriorly of said case unit and reservoir with the exception of said intake.
